UNITED STATES PATENT OFFICE.

JACOB G. CARMICHAEL, OF SEATTLE, WASHINGTON.

BRUSH-RECEPTACLE.

1,110,533.

Specification of Letters Patent. Patented Sept. 15, 1914.

Application filed June 11, 1913. Serial No. 772,989.

To all whom it may concern:

Be it known that I, JACOB G. CARMICHAEL, a citizen of the United States, residing at Seattle, in the county of King and State of Washington, have invented a certain new and useful Improvement in Brush-Receptacles, of which the following is a specification.

My invention relates to improvements in air-tight receptacles that are adapted to contain paint brushes, shellac brushes and the like, and the object of my improvement is to provide such receptacles wherein such brushes may be placed, immediately after being used and while they are still saturated with liquid, to protect such brushes from dust and dirt and to prevent the evaporation of the liquid with which they are saturated thus to maintain them in a soft and pliable condition until they are again required to be used. I attain this object by devices illustrated in the accompanying drawing, wherein—

Figure 1 illustrates a structure adapted to contain a plurality of brushes by a view in longitudinal vertical-section, Fig. 2 shows the same by a view in vertical cross-section on broken line x, x of Fig. 1, and Fig. 3 illustrates a modified form of structure adapted to contain a single brush by a view in side elevation wherein a portion of the structure is shown as broken away to disclose internal parts.

Like reference numerals indicate like parts throughout the drawings.

Referring to the drawings, 4 is an oblong rectangular inclosing case, preferably of sheet metal, as of tin, divided into compartments 5, 6, and 7 by partitions 8 and 9. The top side of the compartment 5 is provided with an oblong opening whose edges are provided with a downwardly projecting flange 10 and within such opening is disposed a cap-cover 11 within the central portion of which rises a tapering inclosure 12 adapted to inclose the handle of a brush 16 and within such inclosure 12 are curved flat springs 15 of suitable spring metal disposed one on each of opposite walls of said inclosure to adapt them to engage with and securely hold the handle of brush 16 to suspend such brush 16 so that the ends

of its bristles may not touch the bottom of the case 4. The lower ends of the springs 15 may be fastened to the underside of the flat portion of the cover 11 by solder or by a rivet as shown in Fig. 2.

The compartments 6 and 7 are provided with similar covers but each is adapted for a different size of brush as brushes 17 and 18.

In Fig. 3 I have shown a single brush receptacle 20 of circular form containing a brush 21 suspended by springs 15 whereby the bristles of such brush 21 may not rest upon the bottom of said receptacle, the handle of the brush 21 projecting upwardly within the inclosure 19 in an obvious manner. Thus, in using a structure embodying my invention, when one has ceased using a brush he may immediately project its handle within the inclosure 12 of a cover 11 to be securely held in suspension by the springs 15 and then place the cover 11 in its position in a compartment with the bristles of the brush projecting downwardly within such compartment, whereby such brush may be protected from dirt or dust and whereby it will be maintained soft and pliable since by reason of the air-tight joint between the cover and receptacle it may prevent evaporation of the mixture that has been absorbed by the bristles of the brush.

Of course, any number of compartments may be included in a single structure or a single receptacle may be used and such compartments and single receptacles may be of various forms and sizes to suit various forms and sizes of brushes.

What I claim is:

A receptacle for brushes comprising a case adapted to contain water and the bristle portion of a brush, a cover provided with a downwardly projecting annular portion and a flange of greater diameter than said annular portion to adapt it to cover an opening in the top side of said receptacle, said cover being further provided with an upwardly extending portion which forms an inclosed chamber that is adapted to receive the handle of a brush, and two oppositely disposed flat springs whose lower ends are each secured to the underside of said cover and each of which flat springs is curved and

disposed to project upwardly within said chamber with its upper end in engagement with the wall of said chamber where-
by the handle of a brush may engage with
5 the convex surfaces of said springs thus suspendingly to support said brush.

In witness whereof, I hereunto subscribe my name this 24th day of May, A. D. 1913.

JACOB G. CARMICHAEL.
